FIG. 1

FIG. 2

FIG. 3

FIG. 4

FIGURE 1 is a front elevation of a lamp illustrating my new design;

FIGURE 2 is a side elevation of the lamp;

FIGURE 3 is a top plan view of the lamp with portions of the burner member omitted for convenience of illustration; and

FIGURE 4 is a bottom plan of the lamp.

The undisclosed rear of the lamp is substantially the same in appearance as the front shown. The undisclosed side of the lamp is substantially the same in appearance as the side shown.

The dominant features of my design reside in the portions shown in full lines.

I claim:

The ornamental design for a lamp, as shown and described.
